(57) **CLAIM**

The ornamental design for a combined hood and eye mask, as shown and described.

DESCRIPTION

FIG. 1 is a perspective view of a combined hood and eye mask;

FIG. 2 is a front view of the combined hood and eye mask of FIG. 1;

FIG. 3 is a rear view of the combined hood and eye mask of FIG. 1;

FIG. 4 is a top view of the combined hood and eye mask of FIG. 1;

FIG. 5 is a bottom view of the combined hood and eye mask of FIG. 1;

FIG. 6 is a left side view of the combined hood and eye mask of FIG. 1;

FIG. 7 is a right side view of the combined hood and eye mask of FIG. 1; and,

FIG. 8 is a perspective view of the combined hood and eye mask of FIG. 1, showing an example of use of the combined hood and eye mask.

Broken lines in the drawings depict features that form no part of the claimed design.

1 Claim, 3 Drawing Sheets
